Inventor

W. C. Parcells.

UNITED STATES PATENT OFFICE.

WILLIAM C. PARSELLS, OF WATERVILLE, NEW YORK.

GRINDING GLOBE-VALVE SEATS.

SPECIFICATION forming part of Letters Patent No. 502,982, dated August 8, 1893.

Application filed August 10, 1892. Serial No. 442,665. (No model.)

To all whom it may concern:

Be it known that I, WILLIAM C. PARSELLS, a citizen of the United States, residing at Water-
ville, in the county of Oneida and State of New
5 York, have invented certain new and useful
Improvements in Devices for Grinding Globe-
Valve Seats and Globe-Valve Stems; and I
do hereby declare the following to be a full,
clear, and exact description of my invention,
10 which will enable others skilled in the art to
which it appertains to make and use the same.

My invention relates to improvements in
devices for grinding and smoothing globe
valve seats and globe valve stems, which have
15 become roughened, and thereby unfit for use,
by wear, and it consists in a device which
will enable this result to be accomplished
without the necessity of removing the valve
seat from its position, which will be herein-
20 after fully described, and particularly pointed
out in the claim.

The object of my invention is to produce
a regrinding tool for valve seats and valve
stems which can be applied and accomplish
25 its purpose without removing the valve seat
from the pipe in which it may be situated,
whose construction shall be such that there
shall be no danger of marring the threads of
the valve throat, which can be very quickly
30 and easily placed in position for operation,
and which shall be inexpensive, simple, and
portable. This object I accomplish by the
use of a grinding tool consisting of a cylinder
of emery or corundum, irremovably secured
35 in a soft metal band, and provided at its cen-
ter with a square mortise, or hole, extending
through it, in which may be placed bits of
suitable size and shape, by which the said
grinder can be revolved. The grinding tool
40 is held in position on the valve seat by means
of the bit working through an upright exten-
sion on the top clamp, of two clamps between
which the pipe fitting, in which the valve
stem to be trued is situated, is held, the lower
45 of said clamps being formed with a spherical
depression adapted to receive the rounded
lower surface of said pipe fitting, and being
connected to the top clamp by means of
screws.

50 My invention is fully represented in the
drawings accompanying and forming a part

of this application, in which the same refer-
ence numerals refer to the same or correspond-
ing parts, and in which—

Figure 1 is a front elevation of my improved 55
valve grinding device applied to a valve. Fig.
2 is a cross section thereof. Figs. 3 and 4 are
detail views of the grinders, showing differ-
ent forms thereof. Fig. 5 is a fragmentary
detail view of the valve stem, showing the ap- 60
plication of grinder F.

Referring to the drawings, A represents the
top clamp, and B the bottom clamp of the two
clamps between which the pipe fitting, in
which the valve to be trued is situated, is 65
held.

C represents the bolts connecting the two
clamps, which bolts are provided on their up-
per ends with screw threads, on which work
the thumb screws D. 70

E represents the brace bit, the lower end of
which is squared to enter into the mortise
formed in the grinders F and G, which are
composed of emery or corundum, and are en- 75
circled by soft metal bands H.

The top clamp A, the lower surface of which
designed to rest against the throat of the valve
seat, is formed with the extension A', which
is bored at a perfect angle with the said bear- 80
ing face of the clamp A. The lower clamp B
is formed with the globular depression B',
adapted to receive the globular portion of the
valve, and thereby furnish a bed with suffi-
cient building surface to withstand the strain 85
incident to screwing the clamps together
when applied to the valve. As globe valves
are always turned accurately true at the
throat, and in line with the stem of the valve,
it will be seen that by the simple arrange- 90
ment of clamps thus described, the grinding
tool is certain to operate on the valve seat at
the proper position and angle, and to leave
the seat true for the valve stem, when the
same is replaced.

The grinding tool, which may be in either 95
of the forms designated as F and G, is made
of emery or corundum, and is irremovably
cast into the encircling band H, which is made
of some soft metal such as brass. The tool
may either be made with a flat surface, as 100
shown by G which form is used when grind-
ing flat valve seats, or it may be formed, as

represented by F, with a convex end and a concave end, the concave end to be applied to the valve stem of valves which are formed with wedging surfaces, and the convex end 5 to be applied to the corresponding valve seat, thus enabling both valve stem and valve seat to be properly smoothed by the same instrument. As both forms of valves are formed with a square mortise or hole extending 10 through them, adapted to receive the squared end of the shank E, a simple inversion of the grinding tool is all that is necessary to enable the same to be used either on a valve stem or a valve seat. The grinders will in course of 15 time be worn by use, but they can then be smoothed down to their proper condition again by the use of proper turning tools. The object of making the encircling band H of soft metal is to prevent the threads of the 20 valve throat being injured by the rotation of the grinder, should it strike against the same.

When valves are but slightly worn in their seat, the grinders can be used without the clamps, for the metal bands being smooth, and 25 guided by the throat of the valves, they are held in position while the grinders do their work upon the stem of the valve. Since the grinders are rimmed with smooth metal, the thread inside of the throat of the valve will 30 not be marred by the band flying against them while in operation. When, however, the valves are seriously cut by wear, and need to

be lined up or trued, the clamps A and B should be put in position, and the thumb screws D turned until the pipe fitting is securely held in position, the grinder having first been inserted through the throat of the valve, and placed on the valve seat. The projecting end of shank E is then turned by a bit as if boring.

It is evident that the grinding tools will have to be made of different sizes for different sizes of valves. The clamps will not need to be made in as many different sizes as the valves, as one clamp can be used with several 45 different sizes of valves.

Having thus fully described my invention, what I claim as new, and desire to secure by Letters Patent, is—

The combination with the bottom clamp B, 50 provided with the globular depression B', the top clamp A, having its lower surface accurately faced, and provided on its top surface, and at perfect angle with said faced surface, with the hollow extension A', and means for holding said clamp pieces in position on a pipe fitting, of a grinder provided with a stem working through said extension A', substantially as described.

WM. C. PARSELLS.
